RAYMOND H. OLLEY, OF SYRACUSE, NEW YORK, ASSIGNOR TO CROUSE-HINDS COMPANY, OF SYRACUSE, NEW YORK, A CORPORATION OF NEW YORK.

PANEL-BOARD.

1,084,560.

Specification of Letters Patent. Patented Jan. 13, 1914.

Application filed February 18, 1911, Serial No. 609,519. Renewed October 30, 1911. Serial No. 657,621.

To all whom it may concern:

Be it known that I, RAYMOND H. OLLEY, of Syracuse, in the county of Onondaga and State of New York, have invented a new and useful Panel-Board, of which the following is a specification.

This invention relates to panel boards and has for its object the production of a particularly simple and efficient electrical appliance and parts associated therewith, to be used in a panel board; and the invention consists in the combinations and constructions hereinafter set forth and claimed.

In describing this invention reference is had to the accompanying drawing in which like characters designate corresponding parts in all the views.

Figure 1 is a plan of a portion of a panel board embodying my invention. Fig. 2 is a fragmentary view showing the base of the panel board and the cap of the electrical appliance or snap switch in section. Fig. 3 is a fragmentary view showing the bases of the panel board and of the snap switch in section, the cap of the switch being removed. Figs. 4 and 5 are inverted views respectively of the base and the cap of the switch.

1 is the base of the panel board.

2 and 3 are, respectively, pairs of conducting bars mounted on the face of the base, the bars of each pair having their ends 4 spaced apart and opposed to each other and also offset from, that is, raised above the outer face of the base and thickened. 5 is this base of the switch, the base being formed of a block of insulation and having a central recess 6 and also a set of recesses 7 opening into diametrically opposite sides of the central recess and through the outer side faces of the base 5, the recesses 7 being located at diametrically opposite corners of the base and forming projections 8 located on other diametrically opposite corners of the base 5 and between said recesses 7. The base 5 is also formed with ribs 9 on its lower face for extending between the opposing ends 4 of the bars of each pair of conducting bars 2 and 3 and also with projections 10 arranged at a right angle to the ribs 9, the projections 10 extending between the pairs of conducting bars 2, 3 and the edges thereof engaging such bars.

11 is a pair of terminals located respectively in the recesses 7 and secured therein

by screws 12 extending through passages 13 opening into the base 5 from the rear side thereof, the screws 12 threading into said terminals 11. 14 is a second set of terminals mounted on the upper faces of the projections 8 and secured thereto by screws 15 extending through passages 16 opening through the rear side of the base 5. Portions of the terminals 11 and 14 project into the central recess 6 into the path of the switch arms to be described.

17 and 18 are respectively pairs of screws extending through the terminals 11 and 14, respectively, from the front side of the panel board through the base 5 and into the thickened raised ends of the conducting bars 2, 3, one member of each pair of screws 17 or 18 extending into one of the bars 2 and the other member of said pair of screws 17 or 18 extending into one of the bars 3.

19 is the rotary shank of the snap switch, the shank being located axially of the central recess 6 and having two sets of switch arms or knives 20, 21 for coacting, respectively, with the terminals 11 and 14.

22 is a cup-shaped cap fitting over the base 5, and the terminals mounted thereon the cap being formed of insulation and having cutouts 23 in the edge of its open end for receiving the bars 2, 3, said edge of the cap resting on the face of the base of the panel board and the side walls of the cutouts coacting with the edges of the bars 2, 3 to prevent turning of the cap.

24 is a button or hand engaging piece threading on the portion of the shank 19 which extends through the opening 25 in the closed end of the cap 22, the button 24 also serving as a nut to hold the cap in position with its lower edge in engagement with the base of the panel board. The cap is also formed with a suitable sight opening 26 through which an indicator associated with the switch and bearing the words "Off" and "On" may be read.

The construction herein described is particularly advantageous in that the terminals of the switch are easily accessible upon the removal of the cap. Heretofore the base has been formed with recesses which do not open through the side faces of the base so that the terminals are only accessible from the top or upper side of the base of the switch; and the cap has heretofore been formed compara-

- tively shallow and rested on the upper face of the base, such cap being formed of metal so that insulation had to be placed on the inner face of the cap. This construction is 5 also advantageous because the great depth of the cap affords a large amount of insulating fire proof surface, reducing to a minimum the fire hazard and the liability of injury to parties having access to this panel-board, and because after the removal of the cap the switch may be removed from, or replaced on, the front of the base of the panel-board and without access to the rear of such base.
- 10 15 What I claim is:
1. The combination with a panel board having conducting bars; of an electrical appliance mounted on the panel board comprising a base of insulation, terminals mounted on the base and being connected to the conducting bars, a switch comprising arms for connecting opposite terminals, and a cap of insulation fitting over the base, the terminals and the arms and entirely inclosing the 20 same and engaging at its lower edge with the panel board, the switch also comprising a shank extending upwardly through the top of the cap and having a handle at its outer end, the handle also serving to hold 25 the cap with its lower edge engaging the panel board, substantially as and for the purpose described.
  2. In a panel-board structure and in combination, a panel-board base, pairs of conducting bars spaced apart and secured to the face of said base, opposing ends of the members of each pair being separated from each other and from the base, a switch-base of insulation supported on the said ends of 30 said members, switch-members carried by the switch-base and electrically connected to corresponding conducting bars and exposed at the outer end of said switch-base, a stationary removable cap of insulation inclosing the switch-base and said switch members and having edge portions resting on the panel-board base between the pairs of conducting bars and adjacent side edges of said bars, a shiftable switch-member also inclosed by the cap, a rotatable shank carrying the shiftable switch-member and having a part extending through the cap, and an operating member mounted on said shank and coöperating with the cap for holding 35 it in place, substantially as and for the purpose described.
  3. In a panel-board structure and in combination, a panel-board base, conducting bars secured to the face of said base, a 40 switch base of insulation mounted directly on said conducting bars free from the first-mentioned base, switch members carried by the switch base, and fastening members arranged above the first-mentioned base and

extending through the switch base and having their ends connected to said conducting bars and switch members, the fastening members electrically connecting said bars and members and supporting the switch base upon the conducting bars, substantially as and for the purpose set forth.

4. In a panel-board structure and in combination, a panel-board base, conducting bars secured to the face of said base and having raised portions thereof spaced apart from the face of the base, a switch base of insulation mounted directly on said raised portions of the conducting bars free from the first-mentioned base, switch members carried by the switch base, and fastening members movable from the face of the switch base through portions of said switch members and the switch base into detachable engagement with the raised portions of the conducting bars, the fastening members electrically connecting said bars and members and supporting the switch base upon the raised portions of the conducting bars, substantially as and for the purpose specified.

5. In a panel-board structure and in combination, a panel-board base, pairs of conducting bars spaced apart and secured to the face of said base, opposing ends of the members of each pair being separated from each other and from the base and thickened, 90 a switch base of insulation mounted directly on said ends of the conducting bars and having projections on its lower face interposed between opposing end faces and opposing side faces of said ends of the conducting 95 bars, switch members carried by the switch base, and fastening members movable from the face of the switch base through portions of said switch members and the switch base into detachable engagement with said ends 100 of the conducting bars, the fastening members electrically connecting said bars and members and supporting the switch base upon said ends of the conducting bars, substantially as and for the purpose described.

6. In a panel-board structure and in combination, a panel-board base, conducting bars secured to the face of said base, and a switch comprising a base of insulation above the conducting bars, an operating shank projecting above the second-mentioned base, and an insulating cup-shaped cap entirely inclosing the switch base and having the edge of its open end engaged with the first-mentioned base and provided with cutouts 105 therein for receiving the conducting bars, walls of the cutouts coating with side edges of the conducting bars for preventing the turning of the cap, and the closed end of the cap being provided with an opening through 115 which the shank of the switch extends, said switch also comprising an operating member mounted on the projecting end of the shank 120 125

and coacting with the closed end of the cap for holding said cap in position against the first-mentioned base and with the conducting bars in said cutouts, substantially as and for the purpose set forth.

In testimony whereof, I have hereunto signed my name in the presence of two at-

testing witnesses, at Syracuse, in the county of Onondaga, in the State of New York, this 18th day of January, 1911.

RAYMOND H. OLLEY.
